METAL CHAIR CONSTRUCTION

John B. O'Connor, Aurora, Ill., assignor to Lyon Metal Products, Incorporated, Aurora, Ill., a corporation of Illinois

Original application July 22, 1946, Serial No. 685,427. Divided and this application February 12, 1948, Serial No. 7,858

6 Claims. (Cl. 155—194)

1

This invention relates to an improved construction for metal chairs, and more particularly to folding metal chairs.

This application is a division of my prior application Serial No. 685,427, filed July 22, 1946, now Patent No. 2,458,095, granted January 4, 1949.

Among the objects of the present invention is to provide a metal chair wherein the frame members are of channel shape in cross section, and wherein the leg members are joined to the main frame by means of a rugged, relatively cheap construction.

Yet another object of the invention resides in providing a folding chair having channel-shaped legs joined to channel-shaped portions of a frame member by means of a pivotal joint which is both rugged in construction, cheap in manufacture and assembly, and simple and ornamental in appearance.

These and other objects of invention will be apparent from a perusal of the following specification when taken in connection with the accompanying drawing, wherein:

Figure 1 is a perspective view of a chair made in accordance with the present invention, and showing the legs joined in the manner of the invention described herein;

Figure 2 is a view showing the chair with the legs in folded condition;

Figure 3 is a side sectional view of a chair having the rear legs pivotally connected to the main frame;

Figure 4 is an enlarged detail perspective view partly in section of the construction shown in Figure 3, showing the pivotal joint between the rear legs of the chair and the front channel-shaped frame member; and

Figure 5 is a section taken on the line 5—5 of Figure 4.

Referring now to the drawings, and particularly to Figures 1, 2 and 3, the chair in general comprises a main frame, preferably formed from a metal channel bar. In this construction I prefer to make the main frame of U-shaped construction so that the lower parts will provide two front feet and so that the upper portion thereof may support a back. In any event, the main frame comprises a pair of opposed, spaced apart, main frame members 10 which are channel or U-shaped in cross section, each including an intermediate wall or web member 10d and two integral, spaced apart flanges 10a and 10b which lie parallel one to the other and normal to the intermediate wall 10d. The leg portions of the

frame members 10 are braced by a cross brace 11 whereby the lower ends are rigidified and have no tendency to turn. A pair of substantially similarly shaped but shorter channel bars 12 are provided as rear legs for the chair. It will be noted that these channel bars are arranged with the opposed flanges 12a and 12b thereof facing inwardly whereby the relatively smooth, flat, outer walls of the intermediate or web portions 12d of the channel bars both face outwardly so that they can be disposed in common planes with webs 10d, as hereinafter set forth, thereby to improve and enhance the appearance of the chair, and whereby the channel formation of the leg and frame members may be utilized for providing a simple type of pivotal connection or interconnection between the two shorter rear legs 12 and the opposed frame members 10.

It will be noted that the upper portion of each 20 of the rear legs 12 has its flanges 12a and 12b cut away and terminating substantially at the zone 12c, and that furthermore the intermediate web portion 12d of each of these channel-shaped rear legs projects beyond the zone 12c where the 25 flanges terminate to provide an outwardly extending tab which is rounded at its outer end, whereby to provide clearance upon the pivotal swinging movement of the rear legs relative to the main frame members 10. The rear shorter legs 12 are braced by the cross brace 14.

Improved means is provided for preferably pivotally connecting these rear legs to opposed portions of the frame members 10, and the construction of this connection is specifically illustrated more clearly in Figures 4 and 5.

The upper portions of the front frame members, where they are joined together, are provided with a sheet metal back 15 and a preferably sheet metal seat 16 is pivotally secured to the frame by pivots 17. In addition, each rear corner of the seat is provided with a projection 18 carrying a lug 19 slidable within one of the associated channels of the rear legs 12. In addition, each rear leg within the channel carries a stop member 20 for limiting the upward movement of the associated lug 19 therein. The lower ends of the channel bars 10, and the rear legs 12 carry feet affording a firm and solid support construction for the chair.

Figures 4 and 5 illustrate the improved means 50 for pivotally interconnecting the main frame or channel members 10 to the rear supporting channel-shaped legs 12. To this end, a pair of brackets 25 suitably interconnect the spaced frame members 10 of the main frame with the rear legs 12.

Each of these brackets preferably comprises an inner portion 25a which is preferably of a shape and size snugly to fit between the bottom flange portions 10a and 10b of each of the channel frames 10. In the present instance this inner end portion 25a is shown substantially of rectangular dimensions and it is constructed so as to provide an edge 25f which snugly contacts and lies against the base of the flange 10a so as to prevent the inner end 25a from turning in the channel. The opposite flange 10b of each of the frame members 10 is cut away to provide a slot 25g which is located somewhat closer to the junction of the intermediate or web portion 10d and flange 10b than it is to the outer edge of this flange 10b. Each bracket 25 is secured in place by a rivet 30 or the like and includes an outwardly, or in the present case, rearwardly, projecting extension or free tab 25b, the outer end of which is rounded and centrally perforated. In addition it is to be noted that the plane of this extension or free tab 25b is offset as at 25c from the plane of the inner portion 25a of the bracket. The extension 25b of the bracket passes more or less snugly through the slot 25g of the flange 10b in a direction toward the associated rear leg 12. This extension 25b of each bracket is pivotally connected to the top portion of a rear leg member 12. Figures 4 and 5 show the connection of the upper portion of one frame member 10 with one rear leg 12, the other connection being identical in construction. In Figures 4 and 5 the top-most portion of the web portion of the rear leg is shown with the projecting rounded tab of the web portion 12d disposed in register with the tab 25b of the bracket member and with the central perforations of the tab 25b and the tab or projecting end of the web portion 12d in register. In addition there is an insert providing extra thickness and comprising a sheet metal piece 20a which likewise is rounded at its top as at 20b to correspond with the curvature of the portions 12d and 25b, and this insert 20a is provided with a perforation registering with the perforations in the bracket extension or tab 25b and in the upper wall 12d of the rear leg members. This insert 20a in the present instance extends downwardly between the flanges 12a and 12b and is of sufficient thickness and width snugly to fit between the basal portions of these flanges, whereby to preclude a twisting action between this portion of the insert and the flanges and intermediate wall portion of the associated rear leg member. This insert piece 20a is fastened to the intermediate wall or web portion 12d in any desirable manner, such as by welding or the like. A pivot pin 26 passes through the registering perforations of the bracket extension 25b, the insert 20a, and the upper end of the web portion 12d of the rear leg, whereby pivotally to interconnect the associated rear chair leg 12 to the associated front channel member 10. Due to the lateral offset 25c of each bracket 25, when the legs are in closed position the outer faces of the web portions of the rear legs will more accurately align with and be in the same planes as the outer walls of the intermediate walls or webs of the main frame members. This double wall thickness through which the pivotal pin extends likewise provides a connection of increased strength between the bracket 25 and the rear leg. The downwardly extending portion of each insert 20a lies substantially flush against the side flanges of a rear leg 12 to be aligned thereby and held from twisting. This action is

similar to that of edge 25f of the inner portion 25a of the bracket aligning against the base of the flange 10a whereby only forces of shear, as distinguished from forces of rotation, are transmitted. With respect to the bracket 25, the wall surfaces of the slot or cutout in the rear flange 10b of the main frame member 10 further cooperate by engagement with the edges of the bracket passing therethrough to prevent rotation thereof.

10 In the present construction each extra thickness insert 20a lying between the flanges 12a and 12b is continued inwardly and downwardly and is formed at its lower end with a downwardly concave arcuate flange, providing the stop 20 for cooperation with one of the lugs 19 hereinbefore described.

15 It will thus be seen that the bracket 25 provides an extremely simple type of means for flexibly and rigidly attaching the rear legs to the front frame members 10 while at the same time permitting the aligning of the outside of each leg with the outside of the adjacent chair frame member 10.

20 In the present construction the insert providing the stop 20 is also extended to the top of the rear leg, as shown in Figure 4, to provide additional thickness at this point and likewise so that it may be riveted or welded to the top of the leg to make this a positive attachment, there-25 by making certain that if for any reason a spot weld fails, the stop will still function since it is held in position by rivet 26. Also, in manufac-30 turing, or rather, in assembly, this construction provides an accurate and positive location for the stop 20, making it unnecessary to provide any 35 other means of jigging for location. In one manner of assembling this device I merely register the hole in the insert 20a with the hole in the rear leg 12 and spot weld the insert to the 40 leg 12 so that after assembly the chair cannot fail. That is, the stop will serve the purpose even though the weld may fail to hold.

45 It is understood, of course, that the insert member 20a need not be formed in such elongated fashion and may not include the stop 20. It is of course understood that the member 20a is usually welded to the channel section, and each rear leg is provided with this same construction.

50 It is apparent that many widely different em-55 bodiments of this invention may be made without departing from the spirit and scope thereof, and therefore it is not intended to be limited except as indicated in the appended claims.

Having thus described the invention, what is claimed as new and desired to be secured by Letters Patent is:

1. A folding chair comprising a main frame providing a pair of spaced front legs, and a pair of rear legs respectively secured to the front 60 legs by pivot connections at the upper ends of the rear legs, said front legs and rear legs comprising channel members each including web and flange portions with the rearward flange portion of each front leg having a cut-out portion therethrough, each of said pivot connec-65 tions comprising a bracket secured to a front leg channel and extending rearwardly through the cutout portion thereof, the associated rear leg channel having a reinforcing member lying 70 substantially flush with the web portion of the channel and extending downwardly from the upper end thereof a predetermined distance to provide a channel web portion at the upper end of the rear leg channel of increased thickness, 75 each bracket member and the web of the asso-

ciated reinforcing member and rear leg channel being provided with aligned openings, and a pivot member projecting through said openings and providing a pivot fulcrum between the front and rear channel legs.

2. A metal chair construction comprising a pair of opposed side frames the lower ends of which form two spaced front legs, said side frames having registering opposed spaced portions of somewhat U-shaped section each including an intermediate wall and opposed flanges integral with and disposed in parallelism at right angles to said intermediate wall, a pair of rear leg members having portions of channel-shaped cross section, the channel-shaped portion of each rear leg including an intermediate wall and opposed parallel walls integral with and extending at right angles to said intermediate wall to provide spaced flanges, the upper end of the intermediate wall of each rear leg extending beyond its adjacent flanges to provide a free tab having a central perforation, and a bracket for each side frame having an inner end fitting rather snugly between the spaced flanges and against the intermediate wall of such side frame and with an edge of the inner end substantially in contact with the base of one of the flanges of such side frame, the opposite flange of each such side frame having a cutout portion through which the opposite end of the associated bracket projects, said projecting opposite end of each bracket having a central perforation registering with the central perforation in the associated tab, and pivot pins passing through said registering perforations whereby pivotally to interconnect each of the rear legs with said side frames.

3. A metal chair construction comprising opposed frame members connected together and having portions of generally channel-shaped cross section and each including an intermediate wall and opposed spaced apart flanges integral therewith and extending at right angles thereto in parallel relation, the lower portions of said frame members forming front legs for the chair, a pair of rear leg members having portions of generally channel-shaped cross section, the channel-shaped portion of each rear leg including an intermediate wall and opposed flanges integral with and extending in parallelism at right angles to said intermediate wall, the upper portion of the intermediate wall of each such rear leg extending beyond its adjacent opposed flanges to provide a free tab, said free tab having a substantially centralized perforation, and one of the flanges of each of the first mentioned opposed frame members having a slot formed therein, a bracket for each frame member having a relatively broad rectangular inner end portion, the free edge of which is disposed to lie against the base of the flange of such frame member opposite to the slotted flange thereof and with its side face in contact with the inner surface of the intermediate wall of said frame member, each bracket having a narrower portion extending substantially snugly outwardly through a slot, and said outwardly extending portion being bent out of the plane of said rectangular portion and terminating in a somewhat rounded tab portion having a centralized perforation, means for fastening each rectangular portion of the brackets to the intermediate wall of a frame member between the spaced flanges thereof, a reinforcing member of sheet metal having a portion disposed in the upper channel of each of said rear leg members

between the flanges thereof and fixed therein, and each such reinforcing member having its upper end projecting beyond said flanges, and abutting the free tab of a bracket, the perforation in each bracket tab being aligned with the perforations in the upper portion of a rear leg member and its reinforcing member, a pivot pin passing through each set of such aligned openings and connecting a rear leg to one of said brackets, and means holding said rear leg members in proper spaced relation to bring the outer sides thereof flush with the outer sides of the opposed frame members as the chair is placed in a folded condition.

15 4. A folding chair comprising a pair of spaced front legs and a pair of rear legs, each of said legs having portions of generally channel-shaped cross section including an intermediate wall and opposed spaced apart parallel flanges integral with the intermediate wall and extending substantially at right angles thereto, one of the flanges of each of said front legs having a slot therein, a bracket for each front leg and having a body portion disposed in the channel portion of a front leg and in contact with the intermediate wall thereof and between the two parallel flanges thereof, said body portion of each bracket being shaped substantially to engage said parallel flanges whereby to prevent turning within the flanges of the front legs, each bracket projecting through a slot in the flange of its associated front leg and having a tab projection provided with a central perforation, a reinforcing member rigidly fastened in the upper portion of each rear leg between the flanges thereof, each reinforcing member lying snugly against the intermediate wall of its associated rear legs with its opposed parallel edges lying substantially between the flanges of such rear leg, means for attaching one of said reinforcing members to the intermediate wall of each rear leg, the upper end of each reinforcing member extending beyond the ends of the flanges of its associated leg and having a central perforation registering with the central perforation of the tab of the adjacent bracket, and pivotal pins passing through the registering perforations and pivotally uniting said rear legs to said front legs.

5. A folding chair comprising a pair of spaced frame members, the lower portions of which form front legs of the chair, said spaced frame members having portions of generally channel-shaped cross section each including an intermediate wall and two spaced apart parallel flanges integral with said intermediate wall and extending at substantially right angles thereto, one of the flanges of each frame member having formed therein a slot lying substantially at the juncture of such flange and the adjacent intermediate wall, a pair of brackets, one for each frame member, each bracket having an inner portion shaped to fit rather snugly against the inner face of an intermediate wall and at the bottoms of and between the parallel side flanges thereof, means for fastening each said bracket member to the intermediate wall of its associated frame member, said bracket member having a portion projecting outwardly through one of said slots and providing an outwardly extending tab disposed laterally out of the plane of that portion of said bracket which lies between the flanges of a frame member, the tab of each bracket being centrally perforated, a pair of rear legs each having a portion of channel-shaped cross section including an intermediate wall and two spaced apart parallel flanges integral with such intermediate wall, said

intermediate wall having an upper extension with a central perforation, a reinforcing member rigidly fastened in the upper portion of each rear leg and lying between the flanges and snugly against the intermediate wall thereof, the upper end of each reinforcing member extending beyond the upper ends of the side flanges of its rear leg and substantially registering with said upper extension and having a central perforation registering with the central perforation of said upper extension and with the central perforation of its adjacent bracket tab, and pivotal pins passing through registering perforations and pivotally uniting said rear legs to said spaced frame members.

6. A folding chair comprising a pair of spaced frame members with the lower portions thereof forming the front legs of the chair and having portions of generally channel-shaped cross section and each including an intermediate wall and two spaced apart parallel flanges integral with said intermediate wall and extending angularly therefrom, one of the flanges of each of said side frame members having formed therein a slot lying substantially at the juncture of such flange and the adjacent intermediate wall, a pair of brackets, one for each frame member, each bracket having an inner portion shaped to fit rather snugly against the inner face of an intermediate wall and with its outer edge lying parallel to and adjacent one of the parallel flanges of the associated frame member, means for fastening each bracket to the intermediate wall of its associated frame member, each bracket having an extension projecting outwardly through an adjacent slot and providing an outwardly extending tab disposed laterally out of the plane of that portion of said bracket which lies between the

flanges of the associated frame member, the tab of said bracket being centrally perforated, a pair of rear legs each having a portion of channel-shaped cross section including an intermediate wall and two spaced apart parallel flanges integral with the main wall, the intermediate wall of each rear leg having a perforated end projecting upwardly beyond its side flanges, a reinforcing member rigidly fastened in the upper portion of each rear leg between the flanges thereof and lying snugly against the intermediate wall portion thereof, the upper end of each reinforcing member extending beyond the ends of the side flanges of its associated rear leg and substantially registering with the projecting end of such rear leg, the upper end of each reinforcing member having a central perforation registering with the perforations in the adjacent tab and upper end of the associated rear leg, and pivot pins passing through registering perforations for pivotally uniting said rear legs to said spaced frame members.
